UNITED STATES PATENT OFFICE.

TAKEKICHI ARAMAKI, OF TOKYO, JAPAN.

AIR-HEATING STOVE FOR BLAST-FURNACES AND GAS-PRODUCERS.

1,357,675.

Specification of Letters Patent.

Patented Nov. 2, 1920.

Application filed April 30, 1919. Serial No. 293,653.

To all whom it may concern:

Be it known that I, TAKEKICHI ARAMAKI, a subject of the Emperor of Japan, and a resident of No. 18 Koun-Cho, Mita, Shiba-
5 Ku, Tokyo, Empire of Japan, have invented a new and useful Improvement in Air-Heating Stoves for Blast-Furnaces and Gas-Producers, of which the following is a specification.

10 This invention has reference to a new and useful improvement in gas producers and air heating stoves for blast furnaces, both working under pressure and heat, wherein the brick wall which constitutes the body or
15 shell of the furnace is entirely covered with reinforced concrete, instead of an ordinary iron plate.

20 The object of the invention is to provide a furnace of this character which will be strong, durable, economical, efficient and easy to manufacture.

25 Further objects of this invention are to provide a furnace of the character described which will eliminate the use of the anti-cor-
rosive materials such as are necessary when the outer wall of the furnace is made of metal, and lastly to provide a perfectly tight wall for the furnace so as to prevent the leakage of the gas and air.

30 With the above object in view my invention has particular relation to certain novel features in which the outer wall surrounding the brick work of the furnace is essentially made of reinforced concrete, substantially in
35 substitution of metallic wall.

35 The form of the furnace and general details of construction which may be varied to suit the circumstances, and which are obviously within the province of the designer,
40 and which form no part of the invention, need not be fully described.

45 The accompanying drawings illustrate, by way of example, one application of the invention, wherein Figure 1 is a longitudinal sectional elevation of the heating stove as applied to Robert's type.

Fig. 2 is a longitudinal sectional elevation showing the invention as applied to Dowson's gas producer.

In these drawings the brick work which forms the body of the furnace is designated by the reference numeral 1. 2 is the refractory brick lining thereof. 3 is the reinforced concrete in question covering entire outer surface of the brick work, which is completed by mixing with suitable water proof material or by coating with coal tar in order to make it water proof, if necessary.

The building of furnaces as heretofore constructed with a metallic outer wall has been accompanied with several disadvantages that it not only enhances the cost of manufacture by using expensive iron but at the same time complicates the assemblage of the parts, especially when there is a possibility of involving additional work and labor for preventing leakage of the gas and air.

By the employment of concrete which is non-corrosive, and comparatively heat non-conductive, in lieu of iron plate, I am enabled, besides overcoming the above disadvantages, to provide a durable, efficient but novel furnace, and in fact the above advantages have not been obtained heretofore.

What I claim as my invention, and desire to secure by Letters Patent of the United States, is:—

An air heating stove for blast furnace and gas producer, having a body provided with a brick wall, a refractory brick lining on the inner side of said wall, and a reinforced comparatively heat non-conducting concrete covering on the outer surface of said brick wall.

In testimony whereof I affix my signature in presence of two witnesses.

TAKEKICHI ARAMAKI
